Fig. 4

To all whom it may concern:

Be it known that we, Wadsworth Bissell and Doyle Watt, citizens of the United States, residing at Grand Rapids, county of Kent, State of Michigan, have invented a new, original, and ornamental Design for a Clock Dial, of which the following is a specification, reference being had to the accompanying drawing, forming a part hereof.

Fig. 1 is a front perspective view of a clock dial, showing our new design,

Fig. 2 is an enlarged fragmentary view in section on a line corresponding to line 2—2 of Fig. 1,

Fig. 3 is an enlarged plan view of one of the elements of Fig. 1 corresponding to that shown in Fig. 2; and

Fig. 4 is an enlarged sectional view on a line corresponding to line 4—4 of Fig. 1 showing details of another of the elements of Fig. 1.

We claim:

The ornamental design for a clock dial, as shown.
